MIXER-CHOPPER FOR MEAT OR VEGETABLES OR THE LIKE

Frank E. Golding, Toledo, Ohio, assignor to Toledo Scale
Corporation, Toledo, Ohio, a corporation of Ohio

Filed Dec. 16, 1966, Ser. No. 5,073

Term of patent 14 years

(Cl. D55—1)

Fig. 1

Fig. 2

Fig. 4

FIG. 1 is a front and left-hand side perspective view of a mixer-chopper for meat or vegetables or the like, showing the new design;

FIG. 2 is a rear perspective view of the mixer-chopper shown in FIG. 1;

FIG. 3 is a front perspective view of the mixer-chopper shown in FIG. 1; and

FIG. 4 is a left side perspective view of the mixer-chopper shown in FIG. 1, the side opposite being substantially a mirror image thereof.

I claim:

The ornamental design for a mixer-chopper for meat or vegetables or the like, as shown and described.
